4 Claims. (Cl. 268—64)

This invention relates to high anti-knock gasoline production and it pertains more particularly to improvements in hexane feed stock preparation and hexane isomerization for the production chiefly of neohexane, i.e., 2,2-dimethylbutane.

Heretofore in the production of neohexane by aluminum chloride isomerization (U.S. 2,443,608) a liquid catalyst complex was employed, temperatures upwards of 200° F. were used commercially to obtain feasible reaction rates, corrosion problems were vexatious and neohexane was produced in relatively small conversions per pass which made product fractionation and recycle quite expensive. The object of this invention is to minimize or avoid such problems and difficulties. A further object is to provide an improved method and means for obtaining large quantities of n-hexane-methylpentane charge containing less than about five volume per cent heptanes and substantially free from aromatics, sulfur and other impurities that might be detrimental to aluminum chloride-on-adsorbent isomerization catalyst. Another object is to provide an improved liquid phase hexane isomerization system employing solid aluminum chloride-on-adsorbent catalyst. Other objectives will be apparent as the detailed description of the invention proceeds.

Our invention makes it possible to produce commercially a non-leaded super premium gasoline having an octane number substantially higher than 100. Available naphthas are split by a fractional distillation to obtain light fractions (C_7 hydrocarbons and lighter) and heavy fractions (C_7 hydrocarbons and heavier). The heavy fractions are hydroformed with platinum-on-alumina catalyst at a severity to obtain a reformate having a clear octane number upwards of 90 and such that the heavy reformate produced will have an octane number substantially higher than 100. The reformate is split by fractional distillation to obtain a C_7+ fraction which may have an octane number of about 102–104 which is a major component of the super premium gasoline. The C_7 and lighter fraction of the reformate is combined with the light virgin naphtha fraction and the mixture is depentanized and then dearomatized. The dearomatization is preferably by selective extraction when aromatics are desired as an additional product, but unless the extraction is sufficiently exhaustive to reduce the aromatic content to less than 0.2 volume percent the depentanized stock should be hydrogenated or otherwise treated to insure removal of not only aromatics but also sulfur compounds and any other component which might be deleterious to the isomerization catalyst. The dearomatized charge is then distilled to eliminate heptanes, which is facilitated by the absence of azeotrope-forming aromatics. A hexane stream is thus produced which is particularly suited for isomerization with our aluminum chloride-on-adsorbent catalyst.

Our preferred catalyst is an acid washed and calcined alumina such as the activated alumina of commerce or bauxite on the surface of which there is deposited at least

2

a monomolecular layer of aluminum chloride. When Porocel (an acid washed and calcined bauxite) is employed as the adsorbent the amount of aluminum chloride deposited on it should be in the range of about 15–30 weight percent. Other supports such as silica, silica alumina, $Ca_3(PO_4)_2$, $CaHPO_4$, $MnHPO_3$, etc., may be used instead of adsorbent alumina but the latter is particularly advantageous both from the standpoint of cost and effectiveness. Instead of subliming the aluminum chloride on the support (note Perry "Isomerization of Light Hydrocarbons," Transactions of American Institute of Chemical Engineers, volume 42 (1946), pages 639 et seq.), we meter aluminum chloride powder and powdered Porocel separately into a circulating, noncomplex forming liquid to form a slurry so that the aluminum chloride is more uniformly adsorbed and the $AlCl_3$ is dispersed more nearly over the entire surface area. The liquid is preferably an aliquot portion of the isomerized product. Aluminum chloride-on-adsorbent catalyst is granular in form and may have a particle size in the range of about 4–400 mesh although about 8–40 mesh particles are preferred. The $AlCl_3$ is thus deposited on adsorbent at about 100° to 200° F.

Preferably the purified hexane charge contacts the solid catalyst in a stage-countercurrent system wherein catalyst about to be discarded or regenerated is contacted with incoming charge and recycled hydrocarbons and the final treatment of the charge stream is with freshly prepared catalyst. In each stage of our preferred system the weight ratio of hydrocarbon to catalyst in the contacting vessel is in the range of about 0.5:1 to 2:1, preferably about 0.7:1 to 1:1. In the stirred portion of each vessel there may be about 4 to 5 pounds catalyst per gallon of liquid. The liquid which is introduced to the settler in each stage may contain about 3 to 4 pounds of catalyst per gallon. The catalyst stream leaving the base of the settlers may contain 8–12 pounds of catalyst per gallon while liquid withdrawn from the upper part of the settlers may have only about 0.1 pound catalyst per gallon. About 100–400 and preferably 200–300 parts of catalyst is recycled in the stage for each part catalyst that is discharged and replaced by incoming catalyst.

Many features of the previously known neohexane process (U.S. 2,443,608) may be employed, but generally speaking our improved process may be operated with less aluminum chloride activator and lower hydrogen pressure. Promoter is stripped from the product and absorbed in incoming charge so that less than 1% make-up HCl is usually necessary. The preferred stripping gas is hydrogen from the hydroformer and the incoming charge may dissolve enough hydrogen to make introduction of extraneous hydrogen unnecessary. The charge should contain about 2–20% of naphthenes such as methylcyclopentane and/or cyclohexane. The isomerization is effected in liquid phase at a temperature of 60–180° F. preferably 80–140° F. and ordinarily in the range of 100–120° F. for a period of time which may range from approximately 0.5 to 5 hours.

The invention will be more clearly understood from the following description of a preferred example thereof read in conjunction with the accompanying drawings which form part of the specification and in which:

FIGURE 1 is a schematic flow diagram of our improved neohexane production system showing the charge

preparation and super premium gasoline production; and FIGURE 2 is a schematic flow sheet showing our hexane isomerization system in greater detail.

In a refinery employing two hydroformers (ultraformers see Petroleum Refiner, 33 (9), 162-3 (1954), and Petroleum Refiner, 33 (4), 153-56 (1954)) each having a charge rate, including recycle of about 18,000 to 20,000 barrels per day and having about 12,000 barrels per day of straight run gasoline the total hexane distribution was found to be substantially as follows:

	No. 1 Ultraformer, b./c.d.	No. 2 Ultraformer, b./c.d.	Straight-Run Gasoline, b./c.d.	Total b./c.d.
Component:				
2,2-Dimethylbutane	79	50	96	225
2,3-Dimethylbutane	79	50	191	320
2-Methylpentane	415	250	1,172	1,887
3-Methylpentane	243	149	718	1,110
Normal Hexane	268	166	1,698	2,132
Total				5,624

The system shown in FIGURE 1 makes it possible to utilize hexanes from these sources and the conversion of almost all of these hexanes to neohexane. About 25,000 barrels per day of naphtha charge from line 10 is fractionated in column 11 to obtain about 18,500 barrels per day of light naphtha which is withdrawn through line 12 and about 6,500 of C₇ and heavier hydrocarbons which are withdrawn by line 13 to hydroformer 14. While the hydroforming may be effected by any known technique which is effective for converting the charge substantially entirely to reformate of which the highest boiling 75% will have an octane number of 102-104, the preferred hydroforming technique is Ultraforming as described in the cited references. The reformate produced by the hydroforming step is introduced by line 15 to splitting tower 16 wherein heavy reformate (C₇ and heavier) is removed by line 17 as a bottoms fraction while light reformate (C₇ and lighter) is taken overhead from the fractional distillation tower by line 18 and introduced to depentanizer tower 19 along with light virgin naphtha from line 12. Pentanes and lighter hydrocarbons are taken overhead from depentanizer 19 by line 20 and may be employed largely for blending into regular gasoline. The depentanized light naphtha mixture is introduced by line 21 to dearomatization system 22 which may be an extraction system when benzene and/or toluene is to be separately produced. The aromatics removal may be effected by extraction with a glycol solvent or other commercially available technique (note Udex process, Petroleum Processing, March 1953, pp. 384-7) or by any other extraction system which is adequate for removing substantially all aromatics from the depentanized stream. A particularly desirable aromatics removal system is described in U.S. 2,768,986. If the extraction leaves more than .2 volume aromatics in the depentanized stream additional aromatics may be removed by adsorption, adduct formation, hydrogenation or any other technique known to the art. In this example upwards of about 2,000 barrels per day of aromatic product is withdrawn as a separate product through line 23 although it should be understood that at least a part of the aromatics may be introduced by line 24 into the super premium gasoline. The dearomatization of the hexane stream facilitates removal of C₇ hydrocarbons from hexanes by avoiding azeotrope formation which would unavoidably be encountered in the presence of aromatics. The aromatic free-hexane-heptane stream is introduced by line 25 to distillation tower 26 wherein the C₇ and heavier hydrocarbons are separated and returned by line 27 for introduction into hydroformer 14. The hexane stream which leaves the top of tower 26 by line 28 substantially free from aromatics, sulfur compounds, and other impurities which would be deleterious to isomeriza-

tion catalyst will usually contain an amount of napthenes in the range of about 2-20%. This hexane charge is the feed stock for isomerization system 29 which is shown in greater detail in FIGURE 2. Hydrogen produced as make gas in the hydroformer 14 is passed by line 30 for use in the isomerization system. Make-up catalyst is introduced by line 31 in carrier liquid introduced by line 32, the slurry being passed by line 33 to the isomerization system. Spent catalyst is removed by line 34 and it may either be discarded or regenerated for further use.

The isomerized product stream is introduced by line 35 to a fractionation system diagrammatically represented by tower 36 from which the neohexane product is taken overhead by line 37, cyclohexane is removed as bottoms through line 38 while an intermediate boiling range methylpentane-n-hexane stream is removed by line 39 for recycle to the isomerization system 29. An aliquot portion of the isomerate stream from line 40 or a portion of the cyclohexane stream may be used for preparing the catalyst as hereinabove described. The net amount of cyclohexane produced may be withdrawn through line 42 and returned to the hydroformer particularly if this stream contains appreciable amounts of methyl or dimethyl cyclohexanes. The composition of the isomerized product charge to fractionator 36 by line 35 and the compositions of the overhead removed by line 37 and the sidestream plus bottoms removed by lines 39 and 38 may be substantially as follows:

	Component	Feed	Overhead	Side-stream and Bottoms
2,2-Dimethylbutane (Neohexane)	5,832	5,538		294
2,3-Dimethylbutane (Diisopropyl)	1,253	153		1,100
2-Methylpentane	3,370	113		3,257
3-Methylpentane	1,655	9		1,646
n-Hexane	850			850
Cyclohexane	1,440			1,440
	14,400	5,813		8,587

From the foregoing it will be observed that the neohexane product stream has a phenomenally high neohexane concentration and that by recycle of the other hexanes almost all of the hexanes can be converted to neohexane. Neohexane has a research blending octane number of approximately 100 in heavy hydroformate so that the total gasoline obtained by blending as illustrated in FIGURE 1 in this particular example may have an octane number of the order of 103.

Referring to FIGURE 2 the hexane stream from line 28 together with recycled hexanes from line 50 are introduced at the upper part of absorber 51 wherein it picks up both HCl and hydrogen introduced by line 52, unabsorbed hydrogen being vented from the system by line 53. Make-up promotor HCl may be introduced by line 54 in amounts to bring the total HCl content of the charge to about .1 to 1% e.g. about .2 weight percent. The promotor-containing charge which is saturated with hydrogen then passes by line 55 to reactor 56 which is a vessel about 9 feet in diameter and 25 feet in height provided with a motor driven stirrer 57 and with a 45 degree inclined baffle 58 having an opening 59 for permitting stirred slurry to enter the upper quiescent zone and a funnel-like return 60 having a flapper valve at the end thereof for returning settled solids from the upper quiescent zone to the stirred zone of the reactor. Catalyst is introduced into the stirrer section of the reactor through line 61 at the rate of about 27½ barrels per day of slurry containing about 514 pounds per hour of catalyst. The amount of charge plus recycle introduced by line 55 being about 14,400 barrels per day. The 100 horse power stirrer 57 may be driven at about 1500 to 2000 r.p.m. for obtaining intimate contact of catalyst with charge. About 21,110 barrels per day of liquid is withdrawn from the upper quiescent zone by pump 62 and

introduced by line 63 by settler 64 which may be 8 feet in diameter and 8 feet tall. The stream entering the settler may contain about 3½ pounds of catalyst per gallon. The settled material leaving the base of the settler through line 65 at the rate of about 6,700 barrels per day may contain about 10 to 11 pounds of catalyst per gallon and about 27½ barrels per day of this stream will be discharged through line 66 while the rest of this stream is returned by line 67 to the stirred portion of reactor 56. The 14,400 barrels per day of liquid from the upper part of the settler is passed by line 68 to the next stage of the countercurrent contacting system, this stream containing only about .1 pound of catalyst per gallon.

In this particular example we employ five separate contacting stages, i.e. an initial step, a final step, and three intermediate stages but it will be apparent that *n*-intermediate stages may be employed where *n* is 0 to 5 or more. In the intermediate stage incoming charge is introduced by line 68 and 69 to the stirred portion of reactor 70 into which make-up catalyst is introduced by line 71. A relatively quiescent liquid is pumped from the upper part of vessel 70 by pump 72 and line 73 to settler 74 from which thickened slurry is withdrawn through line 75, a minor portion thereof being withdrawn through line 61 to reactor 56 and the major portion being recycled by line 76 to reactor 70. Each of the *n*-intermediate stages will be substantially the same and therefore only one need be described.

The partially isomerized hexane stream from the settler of the last intermediate stage is introduced by lines 78 and 79 to mixing zone in the final reactor 80 into which freshly prepared catalyst is introduced by line 81. The liquid from the upper quiescent zone in vessel 80 is introduced by pump 82 and line 83 into settler 84 from which the more concentrated catalyst slurry is returned by line 85 and 86 except for the 27½ barrels per day which is passed by line 71 to reactor 70. The final isomerized product is introduced by line 88 to clarifier 89 which may be a sand filter but which is preferably a filter bed formed from adsorptive alumina. Filter-clarified effluent, which is preferably denuded of dissolved aluminum chloride as well as catalyst solids, is passed by line 90 to the upper part of stripper tower 91 at the base of which hydrogen is introduced by line 92, the hydrogen preferably being make gas from the hydroformer. The HCl-enriched stripping gas which leaves the top of stripper 91 may be introduced through line 52 at the base of absorber 51 so that the incoming hexane charge may absorb substantially all of the HCl content therein and may also dissolve a substantial amount of hydrogen.

Stripped isomerate leaves the base of stripper 91 through line 94, is caustic washed in scrubber system 95, water washed in scrubber system 96 and it is preferably dried before being introduced into fractionating tower 97 from which the neohexane product stream is removed overhead by line 98 (which corresponds with line 37 in FIGURE 31). The bottoms from distillation tower 97 are withdrawn through line 99 to fractionating tower 100 although at least a part of such bottoms may be recycled through lines 101 and 50, respectively. The overhead from tower 100 consists chiefly of methylpentanes and normal hexanes and is recycled by line 50 to absorber 51. A cyclohexane stream 102 is withdrawn from the base of tower 100.

An aliquot part of the isomerate may be introduced via line 104 to catalyst preparation vessel 105 into which acid-washed and calcined adsorptive alumina such as Porocel is introduced by feeder 106 and aluminum chloride is introduced by feeder 107. These feeders may be of the type described in U.S. 2,792,152 and the two materials are fed into vessel 105 in such proportions as to give about 1 part by weight of aluminum chloride to 3 parts by weight of alumina. The resulting slurry is withdrawn from vessel 105 by pump 108 and a portion re-

cycled to the base of vessel 105 through line 109 in order that the slurry may remain in uniform intimately mixed suspension at about 80 to 130° F. while the aluminum chloride is being deposited on the adsorptive alumina. 5 The resulting slurry is withdrawn through line 81 for providing make-up catalyst in vessel 80 at the rate of about 27½ barrels per day.

In this example the temperature is preferably about 120-130° F. in reaction vessel 56 and about 90-100° F. 10 in reaction vessel 80 with a gradient therebetween although the temperature may be uniformly about 105-110° F. throughout. The reaction pressure is maintained at about 50 p.s.i.g.; the pressure should be sufficient to maintain liquid phase conversion conditions but unduly high hydrogen pressures retard desired isomerization. 15 Generally speaking the weight space velocity may be about 0.2 part by weight of oil per hour per part by weight of catalyst employed and the catalyst to oil ratio may be of the order of 1:1 and the hold-up time may be in the range of 0.5 to 5 hours.

Catalyst withdrawn from the system through line 66 may be treated to recover the alumina. After drying the alumina may be reemployed in the preparation of catalyst. However, in many instances economics may 20 favor simple disposal of spent catalyst before or after recovering and/or hydrolyzing material deposited thereon.

While a preferred example of our invention has been described in suitable detail it should be understood that modifications and alternative operating conditions will be apparent from the foregoing description to those skilled in the art.

We claim:

1. The method of converting naphtha to an aromatic product and a super premium motor fuel having a clear 30 octane number substantially higher than 100 which 35 method comprises splitting naphtha into a light fraction containing some C₇ and lighter hydrocarbons and a heavy fraction containing C₇ and heavier hydrocarbons, hydro-forming the heavy fraction under a severity to obtain 40 reformate of which the higher boiling portion has an octane number of about 102-104, splitting the reformate into a light fraction containing C₇ and lighter hydrocarbons and a separate heavy reformate fraction, depentanizing the combined light fractions, removing substantially 45 all aromatics from the depentanized light fractions to obtain a dearomatized stream, dehexanizing the de-aromatized stream to obtain a hexane stream and a heptane stream, recycling at least a part of the heptane stream to the hydroforming step, isomerizing the hexane 50 stream which is substantially free from aromatics and which contains 2-20% naphthenes by contacting with aluminum chloride-on-adsorbent catalyst containing about 15-30% aluminum chloride under a pressure sufficient to maintain liquid phase conditions at a temperature in the range of about 60-180° F. for a time to convert a large proportion of the normal hexane and methylpentanes to dimethylbutanes, splitting the isomerization product by fractional distillation to obtain a stream which is chiefly neohexane and a stream consisting essentially 55 of methylpentanes and normal hexane, recycling the latter stream to the isomerization step and combining the neohexane stream with the heavy reformate fraction to produce super premium gasoline having a clear octane 60 number substantially higher than 100.

2. The method of claim 1 which includes the steps of separately metering aluminum chloride and adsorbent alumina into a slurring zone, introducing a liquid into said slurry zone which is inert and unreactive with said aluminum chloride and pumping said slurry in a closed 65 circuit to deposit aluminum chloride on the alumina support at a temperature in the range of about 90 to 160° F.

3. The method of converting normal hexane and methylpentanes to neohexane which method comprises 70 contacting a charge stream consisting essentially of hex-

anes other than neohexane and containing about 2-20% of naphthenes with a solid aluminum chloride-on-adsorbent catalyst slurry in a plurality of stages each operated at a temperature in the range of about 60-180° F., introducing a small amount of make-up catalyst slurry and a large amount of a charge stream to a mixing zone of each stage and intimately mixing the catalyst slurry therein, passing slurry from the mixing zone to a quiescent zone and passing liquid from the quiescent zone to a settling zone in each stage, recycling a minor portion of the liquid and a major portion of the catalyst from the settling zone to the mixing zone in each stage, withdrawing a major portion of the liquid and a minor amount of catalyst slurry from the settler to the adjacent prior stage, withdrawing a minor amount of settled catalyst to the adjacent subsequent stage, and recycling in each stage more than 100 times the amount of catalyst which is continuously added thereto and withdrawn therefrom.

4. An improved countercurrent slurry catalyst contacting system comprising a series of stages wherein each stage comprises

- (1) a contacting vessel having a lower mixing zone and an upper quiescent zone, a stirrer in said mixing zone, a baffle in said vessel arranged to isolate said upper quiescent zone, said baffle having an opening for receiving catalyst slurry from said mixing zone into said quiescent zone and means for returning settled catalyst slurry from said quiescent zone to said mixing zone,
- (2) a settler exterior of said vessel,
- (3) a conduit from said quiescent zone to said exterior settler,
- (4) branched conduit from the base of said exterior settler to recycle by a first branch thereof a major portion of settled catalyst slurry from said settler to said lower mixing zone of said contacting vessel

5

and by a second branch thereof to remove from said settler a minor portion of said settled catalyst,

- (5) an outlet from the top of said exterior settler and,
- (6) an inlet to said mixing zone of said contacting vessel for introducing catalyst slurry and charge stream;

said system further comprising a conduit for introducing a charge stream to the inlet of the mixing zone of the contacting vessel in the first stage of said series; a conduit for introducing fresh catalyst to the inlet of the mixing zone of the contacting vessel in the last stage of said series; a purge conduit for removing said minor portion of catalyst from said second branch of said branched conduit of the first stage; a conduit for transfer of said minor portion of catalyst from said second branch in each stage subsequent to said first stage to the inlet of the mixing zone of the contacting vessel in each preceding stage of said series; a conduit for transfer of charge stream from the outlet at the top of the exterior settler in each stage prior to the last stage into the inlet of the mixing zone of the contacting vessel in each subsequent stage; and a conduit for removal of a product stream from the outlet at the top of the exterior settler in the last stage.
